Akhavan Radiant Lapidaria, Date Available May 31, 2014, Gemology Project, Site Visited on Dec. 11, 2014: https://www.gemologyproject.com/wiki/index.php?title=Akhavan_-_Radiant_Lapidaria (Year: 2014).*Primary Examiner — Gino Colan*Assistant Examiner* — Nicole M. Leech(74) *Attorney, Agent, or Firm* — The Webb Law Firm(57) **CLAIM**

The ornamental design for a gemstone, as shown and described.

DESCRIPTION

FIG. 1 is a perspective view of a gemstone, showing our new design;

FIG. 2 is a front view thereof;

FIG. 3 is a right side view thereof;

FIG. 4 is a left side view thereof;

FIG. 5 is a top plan view thereof; and,

FIG. 6 is a bottom plan view thereof.

The broken lines in the drawings represent portions of the gemstone and form no part of the claimed design.

1 Claim, 6 Drawing Sheets(56)
